UNITED STATES PATENT OFFICE

OSCAR J. G. METZE, OF COLUMBUS, OHIO

RADIO LOG

Application filed March 12, 1931. Serial No. 522,025.

This invention relates more particularly to a log or means for recording the tuning-in number of radio broad-casting stations.

Owing to the large number of such broadcasting stations it is convenient that the log be made on a long strip of paper or other flexible material adapted to receive writing and the principal object of the invention is to provide an improved mechanism whereby the strip can be caused to travel from one spool to another across a stationary hard intermediate surface to facilitate inscriptions thereon without creating tautness or slackness due to the fact that the diameter of the roll of paper becomes larger as it is transferred from one spool to the other and conversely.

Other objects will appear from the disclosure herein.

My improved mechanism contemplates means whereby either spool is directly driven independently of the other and the driving wheel automatically or otherwise shifted from one driving position to the other by mere reversal of the motion thereof.

The invention is embodied in the example herein shown and described, the features of novelty being pointed out in the claims.

In the accompanying drawings—

Figure 1 is a front view of a fraction of a case illustrating the log according to my invention.

Fig. 2 is an elevation of the operating mechanism.

Fig. 3 is a section on the line III—III Fig. 2 looking to the left.

Fig. 4 is a view, on a larger scale, partly in section and partly in full and broken out to illustrate the means whereby the drive wheel shaft is shifted.

Fig. 5 is a sectional detail of the drive wheel on a scale larger than shown in Fig. 2.

In the views 6 designates the case or cabinet in which the mechanism is suitably located. Said case is provided with an opening 6^a exposing the tape on which the log is to be made.

Mounted on a suitable frame 7 behind or below the opening 6^a is a pair of parallel spools 8, 8^a having shafts 9, 9^a, fixed with the heads thereof. Connected in an ordinary

manner with said shafts 9 and 9^a are the opposite ends of a tape 10 so that the tape can be wound onto one spool from the other according to which spool is directly driven. The tape is passed over two small rounded bars or rollers 11, 11 between which is set in the frame 7 below the opening 6 a piece of translucent glass 12 having its face next said opening, ground to help prevent the tape from slipping while receiving inscriptions.

The shafts 8 and 8^a of the spools are each provided with knurled or otherwise roughened pinions 13 located in different parallel planes at right angles to the axis of said shafts, said pinions having tapered portions 13^a leading to the rims thereof, as shown.

Journaled in the frame 7 is a driving shaft 14 having a driving wheel consisting of a moderately soft rubber disk 15 clamped by bolts between smaller metallic heads 16, said driving wheel being secured to the drive shaft 14 by a pin 17 or otherwise so that the wheel shall rotate with the shaft.

One end of the drive shaft beyond the frame has secured to it a knurled wheel 14^a by means of which the drive shaft and said drive wheel thereon can be turned with the fingers of a hand. The other end of the drive shaft is cut out to form two annular grooves 18 and 19, the portion of the shaft between said grooves being cut with one or more grooves 20 correspondingly slanting as respects the shaft, said slanting grooves 20 communicating with said grooves 18 and 19.

The thus grooved portion of said shaft turns in a sleeve 16^a fixed in or projecting outward from the frame 7; and threaded into a hole in said sleeve is a pin 21, the end of which enters said grooves. When the drive shaft is turned with the pin in either of said annular grooves in a direction so that the pin 21 meets in an acute angle with the angular connecting groove the pin will pass the angular groove but when turned in the opposite direction it will tend to enter said angular groove and therefore by a cam action of the wall of the groove shift the shaft longitudinally on its axis. Springs 22 and 22^a are provided at opposite sides of the frame tending to urge the shaft into the slanting grooves.

when the pin 21 is approached by the end of the groove and the slant of the groove is in the general direction of the turning—in other words forms an obtuse angle with the direction of approach. When, therefore, the shaft, after having been turned in one direction in one of the annular grooves to cause a winding of the tape on the appropriate spool for such turning movement and the direction of turning is reversed the shaft is automatically or otherwise shifted to turn the other spool to wind the tape on the other spool. The shifting of the drive shaft compresses the spring 22 and 22^a at that side 15 toward which the shaft is shifted and relaxes it at the other.

The longitudinal shift of the shaft effected by the slanting groove is sufficient to cause the drive wheel to shift from engagement 20 with one of the pinions 13 to the other without manual pressure, hence when the direction of rotation of the drive shaft is reversed the shifting is automatic. Only one of said pinions is directly driven by the drive 25 wheel.

To prevent slippage or overthrow of the tape on the indirectly driven spool when the other is directly driven the frame 7 is provided with a small spring 24 for each of 30 the spool shafts arranged to press on said shafts and engender enough friction to prevent such overthrow.

An electric light, as indicated at 25, can be provided opposite the glass table for illuminating the tape so as to make the inscriptions or printing thereon easily visible in the dark.

The forms of the parts can be changed without departing from the gist of the invention as claimed.

40 What I claim is:

1. In means of the kind described for winding a tape from either of two spools onto the other, a longitudinally shiftable drive shaft having a drive wheel thereon to directly 45 drive either one only of said spools, said drive shaft also provided with a pair of spaced annular restraining grooves connected by a cross groove and a fixed pin to enter said groove adapted to effect the longitudinal 50 shifting of said shaft when the rotation thereof is reversed.

2. In means of the kind described for winding a tape from either of two spools onto the other, a longitudinally shiftable drive shaft 55 having a drive wheel thereon to drive either one only of said spools, said drive shaft also provided with a pair of spaced annular grooves connected by a cross groove slanting to the axis of the shaft, and a fixed pin entering said groove adapted to effect the longitudinal shifting of said shaft when the rotation thereof is reversed.

3. In means of the kind described for winding a tape from either of two spools onto the other, a longitudinally shiftable drive shaft

having a drive wheel thereon to drive either one only of said spools, said drive shaft also provided with a pair of spaced annular grooves connected by a cross groove, a fixed pin entering said groove, and oppositely 70 operating springs to urge said cross groove to engage said pin and cause the same to enter the opposite annular groove when the shaft is turned in one only of its two directions of rotation.

4. In means of the kind described for winding a tape from either of two spools onto the other, a longitudinally shiftable drive shaft provided with a drive wheel to drive either one only of said spools and provided 80 with a pair of spaced annular guiding means connected with a slanting cross guiding means, fixed means to engage said guiding means, said fixed means and said slanting guiding means adapted to cause the shifting 85 of the shaft longitudinally from engagement of said fixed means with one of the annular guiding means into engagement with the other annular guiding means when the rotations of the shaft is reversed.
